FLUID COMPRESSOR

Filed April 22, 1929

UNITED STATES PATENT OFFICE

HALBERT B. HALVORSEN, OF MICHIGAN CITY, INDIANA, ASSIGNOR TO SULLIVAN MACHINERY COMPANY, A CORPORATION OF MASSACHUSETTS

FLUID COMPRESSOR

Application filed April 22, 1929. Serial No. 357,179.

My invention relates to fluid compressors and particularly to unloading mechanisms for compressors.

An object of my invention is to provide an improved compressor unloading mechanism. Another object is to provide improved means for unloading a plural stage compressor wherein unloading of the high pressure cylinder is delayed for a time after unloading of the low pressure cylinder. In certain types of unloading mechanisms for compound compressors, a pilot valve is connected to the receiver tank and operates in response to receiver tank pressure to cause actuation of devices on each cylinder for effecting unloading of both cylinders almost simultaneously. It will therefore be noted that when the high pressure cylinder is unloaded at the same time as the low pressure cylinder, the compressed air or gas in the intercooler will be lost. With my improved unloading mechanism the unloading device proper for the high pressure cylinder is not operated until a certain time after the low pressure cylinder is unloaded, thereby giving the high pressure cylinder a chance to pump out the fluid from the intercooler. Thus the energy which is stored in the compressed fluid in the intercooler is not lost. Other objects and advantages of my invention will appear during the course of the following specification and claims.

My invention preferably contemplates unloading devices for the high and low pressure cylinders which are actuated to unloading position by fluid pressure, and a pressure responsive pilot valve for controlling the supply and exhaust of pressure fluid to and from such devices, the connection leading from the pilot valve to the high pressure unloading device embodying means for delaying the building up of pressure on the high pressure unloading device until a certain time after the low pressure cylinder unloader has been operated. Preferably also means are provided for restricting the flow of pressure fluid between the pilot valve and high pressure unloader in one direction and allowing a relatively free flow in the other direction, whereby the unloading function is

delayed, while permitting a quick reverse operation to cause loading. In one preferred embodiment I have connected a tank and one-way valve having a restricted port therethrough in the line leading from the pilot valve to the high pressure cylinder unloader. Obviously, however, means may be built into the pilot valve for causing the delayed supply of fluid to the high pressure cylinder, or the capacity of the pipe leading from the pilot valve may be sufficient to allow doing away with the tank. These and other modifications are clearly within the scope of my invention as will be readily apparent to those skilled in the art, and it will be noted that the invention in its broader aspects can be practiced in other systems, for example, such as effect unloading by venting pressure and loading by its supply: in such case providing delayed venting of the higher stage unloading device. Moreover, the unloading of the high pressure cylinder may be delayed, but actuation of the unloading mechanism effected differently, as by a pressure switch controlled solenoid.

In the accompanying drawing I have shown for purposes of illustration one preferred embodiment of my invention.

In the drawing,—

Fig. 1 represents a diagrammatic view of a compressor system having my improved unloading means associated therewith.

Fig. 2 is also a diagrammatic view with some parts shown in section, illustrating the construction of some of the elements of my invention and the various pipe connections.

Fig. 3 is a fragmentary view looking in the direction of arrows 3, 3 in Fig. 1.

Fig. 4 is a central vertical section through the high pressure relief valve mechanism.

In Fig. 1 there is shown a compressor of the angle compound type having a low pressure cylinder 6 arranged horizontally and a high pressure cylinder 7 arranged vertically. An intercooler 8 is interposed between the two cylinders which will be understood to have capacity for a considerable volume of compressed fluid. The high pressure cylinder is connected through a discharge pipe 9 to a suitable receiver tank 10 from which com-

pressed fluid may be supplied for any desired purpose. A fluid actuated unloading device 11, which is herein shown as being of the total closure intake type, is connected to the low pressure cylinder. As shown in Fig. 2, the interior of this unloader embodies a longitudinally movable valve 12, connected to a piston 13 reciprocating in a cylinder member 14 arranged directly above the main valve 10 casing. When the valve is closed by the application of pressure on piston 13, the intake for the low pressure cylinder is cut off, thereby causing unloading of the same. The valve and piston are normally held in their upward 15 or unloaded position by means of a spring 15 arranged in cylinder member 14 below the piston. For the purpose of supplying and exhausting pressure fluid to and from cylinder member 14 to cause loading and unloading 20 in response to pressure in the receiver tank, a pilot valve mechanism 16 of suitable construction is connected to the receiver tank by a pipe 17 and the cylinder 14 by pipes 18, 19. The pilot valve, which I have shown merely in 25 outline, since its construction and operation are known in the art, is the well known Penn pilot valve which operates when there is a predetermined high pressure in the receiver tank to open a connection between pipes 17 30 and 18, and when there is a predetermined low pressure in the receiver tank, to close off pipe 17 and connect pipe 18 to a vent leading to the atmosphere.

The high pressure cylinder relief valve 35 mechanism is of the same type as disclosed in a copending application of W. E. Hughes, Serial No. 326,807, filed Dec. 18, 1928, now matured into Patent No. 1,786,114, patented Dec. 23, 1930. Outwardly opening check 40 valves 20 and 21 are connected to opposite ends of the cylinder and these check valves lead to a common connection 22 through which both ends of the cylinder may be vented by means of the vent valve mechanism 23. In 45 the latter mechanism is a valve element 24 adapted to be opened by pressure on the diaphragm 25 and closed by means of spring 26 when pressure on the diaphragm is relieved. When this valve is closed, as when it is desired to load the compressor, a high pressure will very quickly build up between the check 50 valves and the relief valve which will thereafter hold the check valves closed and permit the cylinder to function normally. When 55 valve 24 is opened to unload the compressor, both ends of the high pressure cylinder are vented directly to atmosphere through valves 20, 21 and 24. Now in order best to control the high and low pressure unloaders with the 60 same pilot valve, a branch connection 27 leads off from pipe 18 through a special check valve 28, tank 29, and pipe 30 to the diaphragm chamber of the relief valve mechanism 23. The check valve 28 is so connected that the 65 valve element 31 will open toward the pilot

valve, and through this valve element is a restricted port 32 which will permit a restricted flow from the pilot valve to the delay tank 29 even when the check valve is closed.

In operation, when a predetermined high pressure is reached in the receiver tank, the pilot valve will operate to establish connection between pipes 17 and 18. Pressure fluid will flow freely to cylinder 14 and cause unloading of the low pressure cylinder. Fluid also flows through the restricted port 32 into tank 29, where a pressure is gradually built up. This pressure is transmitted to the diaphragm chamber of the high pressure relief valve mechanism 23. When a sufficient pressure has built up to overbalance the spring 26, the high pressure relief valve is opened, but during the interval between closing of the low pressure intake unloader and opening of the high pressure relief valve the high pressure piston which has continued to reciprocate has pumped out the fluid under intermediate pressure in the intercooler 8. Therefore, when the high pressure relief is finally opened, practically no energy is lost by reason of venting the intercooler to the atmosphere. Now in the reverse operation, when a predetermined low pressure is reached in the receiver tank, the pilot valve vents the line 18 and permits the pressure fluid in cylinder 14 to be exhausted, thereby causing loading of the low pressure cylinder. Simultaneously the diaphragm chamber of the high pressure relief valve mechanism and tank 29 are also vented through pipe 18 and, in view of the fact that the check valve 31 will at this time swing open, the high pressure cylinder will be loaded at about the same time as the low pressure cylinder.

From the foregoing description, it will be observed that I have provided a simple and certain arrangement for conserving power, and that no partially compressed air will be thrown away. It will also be noted that the improved controlling mechanism lends itself to embodiment in existing systems, to provide an improved and more efficient control. While I have in this application specifically described one form which my invention may assume in practice, it will be understood that this form of the same is shown for purposes of illustration and that the invention may be modified and embodied in various other forms, without departing from its spirit or the scope of the appended claims.

What I claim as new and desire to secure by Letters Patent is:

1. In combination with a compound compressor, an unloader for the low pressure cylinder, a device controlling the unloader, unloading means for the high pressure cylinder also connected to said device for control thereby, and means for delaying unloading of the high pressure cylinder a substantial time after unloading of the low pressure cylinder.

2. In combination with a compressor having a plurality of cylinders, a fluid actuated unloader for each of the cylinders, a pilot valve responsive to compressor discharge pressure, and connections from said pilot valve to said unloaders, one of said connections including means for causing a substantial delay between movement of said pilot valve and the actuation of the unloader with which said connection communicates. 70
3. In combination with a compressor having a plurality of cylinders, a fluid actuated unloader for each of the cylinders, a pilot valve responsive to compressor discharge pressure, connections from said pilot valve to each of said unloaders, and means in one of said connections for restricting the flow of fluid in one direction to cause a substantial delay between movement of said pilot valve and actuation of the unloader with which said connection communicates. 75
4. In combination with a compressor having a plurality of cylinders, fluid actuated unloaders for the cylinders, a pilot valve responsive to compressor discharge pressure, connections from said pilot valve to each of said unloaders, and a tank interposed in one of said connections whereby a substantial delay occurs between movement of the pilot valve and actuation of the unloader with which said last mentioned connection communicates. 80
5. In combination with a compound compressor, a fluid actuated unloader for the low pressure cylinder, a pilot valve responsive to compressor discharge pressure for controlling said unloader, fluid actuated means for unloading the high pressure cylinder also connected to said pilot valve for control thereby, and means for delaying unloading of the high pressure cylinder for a substantial time after unloading of the low pressure cylinder. 85
6. In combination with a compound compressor, a fluid actuated unloader for the low pressure cylinder, a pilot valve responsive to compressor discharge pressure for controlling said unloader, fluid actuated means for unloading the high pressure cylinder also connected to said pilot valve for control thereby, and a delay tank interposed in the connection leading from the pilot valve to the high pressure unloader for causing a substantial delay between unloading of the low pressure cylinder and the high pressure cylinder. 90
7. In combination with a compound compressor, a fluid actuated unloader for the low pressure cylinder, a pilot valve responsive to compressor discharge pressure for controlling said unloader, fluid actuated means for unloading the high pressure cylinder also connected to said pilot valve for control thereby, and means in the connection leading from the pilot valve to the high pressure cylinder for restricting the flow of fluid in one direction to cause a substantial delay between movement of said pilot valve and the actuation of the unloader with which said connection communicates. 95
8. In combination with a compound compressor, a fluid actuated unloader for the low pressure cylinder, a pilot valve responsive to compressor discharge pressure for controlling said unloader, fluid actuated means for unloading the high pressure cylinder also connected to said pilot valve for control thereby, means in said connection for restricting the rate of flow of pressure fluid in one direction between the pilot valve and high pressure unloader, and a delay tank interposed in the connection leading from the pilot valve to the high pressure unloader, said flow restricting means and delay tank constituting means for causing a substantial delay between unloading of the low pressure cylinder and the high pressure cylinder. 100
9. In combination with a compound compressor, a fluid actuated unloader for the low pressure cylinder, a pilot valve responsive to compressor discharge pressure for controlling said unloader, fluid actuated means for unloading the high pressure cylinder also connected to said pilot valve for control thereby, an automatic one-way valve in the connection leading from the pilot valve to the high pressure unloader, and means permitting a restricted flow of fluid past said valve even when closed whereby unloading of the high pressure cylinder is delayed for a substantial time after unloading of the low pressure cylinder and whereby loading of the two cylinders occurs simultaneously. 105
10. In combination with a compound compressor, a device for unloading the low pressure cylinder when subjected to pressure, a device for unloading the high pressure cylinder when subjected to pressure, a pilot valve responsive to compressor discharge pressure for controlling supply of pressure fluid to said devices, connections between said pilot valve and said devices, a delay tank interposed in the connection leading from the pilot valve to the high pressure unloader, a check valve opening toward the pilot valve also in the connection leading from the pilot valve to the high pressure unloader, and a restricted port through said check valve permitting a restricted flow toward the high pressure unloader when the check valve is closed. 110
11. In combination with a compound compressor, an unloading mechanism for the low pressure cylinder, an unloading mechanism for the high pressure cylinder, pressure responsive pilot means controlling both of said mechanisms, and means intermediate said pilot means and said high pressure unloading mechanism for delaying the operation of the latter until a material time after operation of the low pressure unloading mechanism. 115
12. In combination with a compound com- 120
13. In combination with a compound com- 125
14. In combination with a compound com- 130

pressor having low and high pressure cylinders, pressure fluid operable unloading mechanism for the low pressure cylinder, pressure fluid operable unloading mechanism for the 5 high pressure cylinder, compressor discharge pressure responsive means for controlling pressure fluid flow towards and from both of said unloading mechanisms, and fluid conducting means for connecting said compressor discharge pressure responsive means with 10 said unloading mechanisms including between the compressor discharge pressure responsive means and the unloading mechanism for the high pressure cylinder means for retarding 15 fluid flow toward said unloading mechanism but not reverse flow relative thereto.

In testimony whereof I affix my signature.
